(57) **CLAIM**

The ornamental design for a handbag eyelets, as shown and described.

DESCRIPTION

FIG. 1 is a front perspective view of the handbag eyelets shown in FIG. 1;

FIG. 2 is a front view of the handbag eyelets shown in FIG. 1;
FIG. 3 is a left side view of the handbag eyelets shown in FIG. 1 (with the right side view being a mirror image thereof);
FIG. 4 is a top view of the handbag eyelets shown in FIG. 1;
and,

FIG. 5 is a bottom view of the handbag eyelets shown in FIG. 1.

The broken line showing of portions of the body of the bag, closure piece, and grommets is for illustrative purposes only and forms no part of the claimed design.
